PACKAGING BAND

Application filed January 25, 1930. Serial No. 423,513.

This invention relates to paper bands having adhesive-carrying end portions, such bands being largely employed for holding laundered shirts in folded conditions, and for 5 various other uses such as packages of money bills, envelopes, and other articles.

Continuously gummed tape is used very largely in the place of string, for securing food products and other articles which are completely enclosed in paper wrappers, and no 10 objection applies to such use because no harm results even if the tape adheres at any portion of its length to such paper wrappers. But to employ continuously gummed tape for 15 enclosing folded shirts or other articles, when nothing is interposed between the tape and the otherwise bare article, would be objectionable for obvious reasons. Such continuously gummed tape is commonly and conveniently supplied from a coil by devices having 20 means for severing the tape at intervals, and usually moistening end portions.

One of the objects of our invention is to provide paper band material which is of indeterminate length, and preferably coiled or folded, with thickened and gummed portions at predetermined intervals, whereby definite lengths of bands may be separated and served from the greater length of material, by the 30 employment of mechanism somewhat similar to the dispensers now used for the ordinary continuously gummed tape, each definite length carrying a limited amount of gum at or near one of its ends, or sometimes at or 35 near both ends as hereinafter explained.

So far as we are aware, the most economical prior method of making paper bands having gum only at the ends, necessitates the cutting of a web of paper transversely, with the result 40 that the strips cut from the web to provide the bands can be no longer than the width of the web. As is well known, the web can be no wider than the limited capacity of the paper-making machine. Consequently 45 such strips or bands can be but a few feet long. However, in such bands the grain of the paper is crosswise because the manufacture of the web results in the grain being lengthwise of the web. Obviously, therefore, 50 since paper is always stronger in the direc-

tion of its grain than transverse of the web, bands which are cut transversely from the web have a crosswise grain and are liable to be torn crosswise. Therefore another object of our invention is to provide paper bands or 55 equivalent articles supplied by a strip of any great indeterminate length the grain of which is lengthwise, whereby tendency to crosswise tearing is reduced.

Another objection to bands of limited 60 length such as just described, is that when they are to be used it is quite difficult to separate them singly from a lot. In handling they become scattered over the bench or table which not only causes spoilage but requires 65 time to pick up for use such as when banding bread, cake, or the like, in large quantities. A further objection to the use of separate individual bands is that they have to be selected from a pile or stock by hand, and the gum 70 moistened by a sponge. This not only consumes time, but the operator's fingers become sticky and dirty which is obviously objectionable, especially when handling food. Such bands can not be practically supplied by dispensing machines because of the variations 75 in paper and glue substances used. When such bands are stacked in a pile, the ends of the bands having the adhesive are the thickest, and consequently only a few of such bands 80 can be in a pile without tipping over from proper piled condition. Therefore another object of our invention is to provide adhesive-carrying band material in such form that 85 individual bands can be taken therefrom and used without disarranging the rest of the supply.

Another object of our invention is to provide paper band material, with adhesive at intervals, the whole being of such 90 construction that portions thereof, at predetermined intervals, can be employed to operate or control necessary portions of a dispenser to facilitate the successive separation of the lengths desired for use.

With the above-mentioned objects in view, and others hereinafter explained, the invention consists in the articles and the method of making them substantially as hereinafter described and claimed.

Of the accompanying drawings:—

Figure 1 is a side elevation of a coil of the band material, which coil may be much larger than illustrated.

5 Figure 2 is a face view of an indeterminate length of one form of the band material, partially broken away to indicate that the sections of the strip may be of any length.

10 Figure 3 is a face and side view of another structure of the band material.

Figure 4 is a face view of another structure of the band material.

15 Figure 5 is a face view of another structure of the band material.

Figure 6 is a face and side or edge view of another structure of the band material.

20 Figure 7 is a face view of another structure of the band material.

Similar reference characters indicate similar parts or features in all of the views.

25 Referring first to Figures 1 and 2, a strip of paper *a*, of the width that may be desired, and cut from a web of paper in the direction of the length of the web so that the grain of the strip will be lengthwise thereof. At intervals spaced according to the length desired for the bands, the strip is transversely perforated as at *a'*, and adjacent to each line of perforations there is adhesively affixed 30 thereto a piece of suitable material such as kraft paper as illustrated at *b*. For the sake of brevity of terminology, the members *b* will be hereinafter referred to as tabs. In most of the forms hereinafter described, the tabs *b* 35 are double-coated with adhesive material; that is, both surfaces are gummed so that their inner surfaces can be secured adhesively to the strip material *a* while their outer or upper surfaces will present adhesive by means 40 of which a band section, when separated from the long strip, can be employed in the usual manner to enclose or wrap the article for which it is intended. As illustrated by Figure 2, the tabs *b* are circular in form, and as 45 illustrated by Figure 4, they are rectangular. In both cases the tabs are of less width than the width of the band, the advantage of which will now be explained.

50 When the end of a band has adhesive extending its entire width, there is always a liability of one side margin of the gummed portion or member becoming stuck to the shirt or other article to which the band is applied by overlapping the gummed portion 55 (moistened as customary) upon the other end portion of the band when the band is wrapped around the article. It is not easy to so align the overlapped portions as to prevent this. But since the tabs *b* are of less lateral area 60 than the bands, leaving entirely ungummed areas of the band each side of the tabs, there is less likelihood of any adhesive contacting with the enclosed article when the bands are applied in the usual manner.

65 The presence of the tabs *b* at spaced in-

tervals along the strip *a* results in the article as a whole being increased in thickness at those points adjacent to the perforations *a'*, and in making the long strip stronger at those points than elsewhere, and reducing liability 70 of the strip being torn apart elsewhere than intended to supply a section of the predetermined length. In other words, the improved strip has the characteristic that if a user should try to tear the strip *a* by hand, the tabs *b* will not only indicate the proper place 75 in the length of the strip to effect severance, but aid in controlling or confining the location of the severance to that point or place. Said increased thickness due to the tabs *b* may 80 also be utilized to control or operate a dispenser mechanism having a severing blade. Owing to this last feature, it is not always necessary to transversely perforate the strip *a*, since the blade of such dispenser will effect 85 separation of the band sections successively.

As indicated in Figure 3, the tab *b* may extend over the line of perforations *a'*, with a free part *b'* forming a flap that is not adhesively secured to the strip *a*. The under 90 surface of the flap *b'* carries gum, but the entire upper surface of the tab and its flap will be left ungummed. Then, when a section is parted on the line *a'*, it will have a gummed tab extending from its end.

95 As illustrated by Figure 5, the line of perforations *a'* is formed in the tab as well as in the strip *a*. When so made, the tab *b* is adhesively secured to the band throughout its area, and also presents an entire dry-gummed outer surface. When the long strip is made this way, each band section will have an adhesive carrier at each of its ends. Such 100 type of packaging band is desirable for some uses, such as when it is desired to prevent the band from slipping off from the wrapped or enclosed article. To effect this, one end of the band can be stuck to the article wrapped, and the other end overlapped upon and stuck to any desired lengthwise portion of the band.

105 In the structure illustrated by Figure 6, no transverse perforations are employed. Sometimes the increased thickness of the strip at intervals, due to the presence of the tabs, enables a band section to be separated by a tearing action guided by the edge of the tab. Said Figure 6 also illustrates the tab *b* as provided with a partially cut out middle portion providing a flap *b'*. In this form, the upper or outer surface of the tab 110 and its flap carry no adhesive. The under surface of the tab and its flap is gummed, but only the marginal areas of the tab are secured to the strip *a*. The flap *b'* is left free, but with its under gummed surface 115 dry so that, when moistened, it can be utilized as a seal.

120 Figure 7 illustrates a structure similar to Figure 4, but the tab *b*, instead of being narrower than the band *a*, is wider, having side 125

extensions *b*" which may be utilized to control or operate a dispenser mechanism, and which also provide marginal portions on which identification or other marking may be exhibited.

Having now described our invention, we claim:—

1. A strip of paper of indeterminate length having tabs adhesively secured thereto at predetermined intervals, the exposed surfaces of said tabs being gum-coated.

2. A strip of paper of indeterminate length the grain of the paper extending lengthwise thereof, said strip having tabs adhesively secured thereto at predetermined intervals, the exposed surfaces of said tabs being gum-coated.

3. A strip of paper of indeterminate length having tabs adhesively secured thereto at predetermined intervals, the exposed surfaces of said tabs being gum-coated and said strip being weakened adjacent to said tabs.

4. A strip of paper of indeterminate length having tabs adhesively secured thereto at predetermined intervals, said tabs being of less width than the strip and the exposed surfaces of said tabs being gum-coated.

5. The method of making packaging-band material, consisting in cutting a strip lengthwise from a web of paper to cause the grain of the paper to run lengthwise of the strip, and adhesively affixing to the strip, at predetermined intervals thereof, tabs having exposed gum-coated surfaces.

35 6. The method of making packaging-band material, consisting in cutting a strip lengthwise from a web of paper to cause the grain of the paper to run lengthwise of the strip, adhesively affixing to the strip, at predetermined intervals thereof, tabs having exposed gum-coated surfaces, and transversely weakening the strip adjacent to said gum-carriers.

In testimony whereof we have affixed our signatures.
